Patented Mar. 14, 1916.

Fig. I.

A diagram of a rectangular container with rounded corners. On the left side, there is a handle consisting of a vertical bar with a circular loop at the top, labeled '10' and '13'. Above the handle is a small circle labeled '9'. On the right side, there is a vertical strip labeled '2' at the top and '4' at the bottom. The strip has a serrated or toothed edge. The top edge of the container is labeled '3'.

Fig. 2.

The diagram shows a headgear assembly. It features a headband with a curved top section labeled '16' and a flat section labeled '5'. A chin strap is attached to the headband, with one end labeled '1' and the other end labeled '12'. The strap passes under the chin and is secured with a buckle labeled '7'. The strap is also attached to a chin cup labeled '11'. The entire assembly is shown in a perspective view.

UNITED STATES PATENT OFFICE.

WILLIAM E. EDWARDS, OF IRVINGTON, NEW JERSEY.

MATCH-BOX.

1,175,414.

Specification of Letters Patent. Patented Mar. 14, 1916.

Application filed October 5, 1915. Serial No. 54,111.

To all whom it may concern:

Be it known that I, WILLIAM E. EDWARDS, a citizen of the United States, and a resident of Irvington, in the county of Essex and State of New Jersey, have invented certain new and useful Improvements in Match-Boxes or the like, of which the following is a specification.

This invention relates more particularly to match boxes for carrying paper folders of safety-matches and is an improvement upon the construction of match box shown in my previous Patent No. 866,268 of September 17, 1907.

The objects of the present invention are to provide a match box or the like in which the carrier is readily and securely mounted in place; to avoid the necessity of riveting or soldering; to thus avoid tedious and expensive operations in manufacture; to simplify and reduce the amount of hand labor in assembling the match-boxes; to provide a construction wherein use will not tend to loosen the carrier from the case-section; to obtain such a construction which will be neat and durable, and to obtain other advantages and results as may be brought out in the following description.

Referring to the accompanying drawings, in which like numerals of reference indicate the same parts throughout the several views, Figure 1 is a perspective view of an open match box constructed in accordance with my invention; Fig. 2 is a plan view of the outside of the case-section; Fig. 3 is a perspective view of a portion of the match box showing the mounting of the carrier therein; Fig. 4 is a perspective view of a certain removable hinge member; Fig. 5 is a transverse sectional view of the case-section looking toward the carrier, and Fig. 6 is a longitudinal section on line A—A of the same.

In the specific embodiment of the invention illustrated in said drawings, the reference numeral 1 indicates the case-section or body portion of a match box or the like having hinged thereto at one end as at 2 a cover 3 normally held closed by a suitable spring 4. Pivoted within the match box, and preferably upon the case-section or body portion, is a carrier 5 adapted to receive a paper or folder of matches 6 and be swung flatwise within the case-section and covered

with the cover-section, or swung outward when the cover-section is opened, as will be readily understood.

In carrying out my invention, the end of the case-section to which the carrier is to be pivoted is cut through at a suitable place 60 preferably providing an elongated hole 7 extending transversely of the case-section, and shown herein as oblong. Adjacent this hole the material forming the case-section is offset or stamped inwardly as at 8 to a plane 65 substantially parallel to the plane it occupied originally and providing a peripheral shoulder 9 between the offset portion 8 and the rest of the case-section or forming a shallow socket in the middle of which is the 70 hole 7.

A removable hinge member 10 is provided which will just fit within the socket in peripheral engagement with the shoulder 9 and of such a thickness that when held 75 against the offset portion 8 of the case-section, the outer surface of the rest of the case-section and the hinge member are flush or in the same plane. However, if so desired the line of division between the hinge member 80 and the case-section may be so embodied in the design of the match box or the engraving thereon that it is unnecessary or not desirable to make the two parts flush and it is accordingly deemed within the scope of the 85 invention to employ any degree of nicety of the fit of the hinge member 10 within the socket desired.

Forming part of the hinge member and projecting through the hole 7 are a pair of 90 longitudinally separated ears 11 through which a hinge pin 12 may be inserted, said pin extending longitudinally of the hole 7 and adapted to pass through both ears 11. Furthermore the ears are so proportioned 95 that the pin 12 when inserted therein will rest at its ends upon the offset portion 8 within the case-section and thereby hold the hinge member seated within the socket. By this construction no other means than the 100 hinge pin is necessary to hold the hinge member in place, which accordingly avoids any further hand labor than merely inserting the pin, so that soldering or riveting is entirely avoided.

Preferably the hinge member is of a shape and construction readily manufactured by machine, and for simplicity is made of one

piece of material having a portion 13 to fit the socket and the outer surface of which is exposed on the outside of the case-section. At one edge of this outer portion 13 of the hinge member is an inner portion 14 bent back flatwise upon the outer portion and having a middle portion of itself cut away as at 15 leaving two strips adjacent its edges, said strips being bowed away from the outer portion 13 and forming the ears 11 for the hinge pin. Obviously the socket for receiving a hinge member which it is desired to have flush with the outer surface of the case-section, must be deep enough to accommodate both the thickness of the inner portion 14 of the hinge member as well as the outer portion 13.

Projecting from the carrier 5 are suitable ears 16 also adapted to take over the hinge pin 12, and in the particular construction shown these ears 16 upon the carrier are upon the outer sides of the ears 11 of the removable hinge member. The hole 7 in the case-section is accordingly made long enough to accommodate the ears on the carrier, and said ears preferably engage a fixed part, such as the ears on the hinge member, for preventing the carrier from moving longitudinally of the hinge pin. Upon the hinge pin, between the ears of the hinge member, is a spring 17, normally tending to swing the carrier outwardly away from the case section.

In assembling the parts of my improved match box, the hinge member 10 is inserted in the socket in the case section with the ears 11 projecting through the hole 7. The carrier 5 is then brought into position so the ears 16 thereon are at the opposite ends of the other ears 11, at which time the hinge pin is started through the ears. With the hinge pin through the first part of ears the spring 17 is put upon the same and given the proper tension and the hinge pin shoved home, in which position it extends through all of the ears and projects at its ends to overlie the offset portion 8 and thereby retain the hinge member in place and the carrier hinged securely to the case-section. The outer surface of the hinge member provides a convenient escutcheon for an initial, monogram, or other engraving, especially as it may be replaced very readily if so desired without discarding the whole match box.

Obviously detail modifications and changes may be made in manufacturing my improved match box without departing from the spirit and scope of the invention, and I do not wish to be understood as restricting myself except as required by the following claims when construed in the light of the prior art.

Having thus described the invention, what I claim is:—

1. In a match box or the like, a case-section having a hole therein, a hinge member having a portion adapted to seat upon the outer side of said case-section and having ears extending through said hole, and a hinge pin extending through said ears and seating upon the inner side of said case-section whereby said hinge member is secured thereto.

2. In a match box or the like, a case-section having a hole therein, a hinge member having a portion adapted to seat upon the outer side of said case-section and having ears extending through said hole, a hinge pin extending through said ears and seating upon the inner side of said case-section, whereby said hinge member is secured thereto, and a carrier hinged upon said hinge pin.

3. In a match box or the like, a case-section having a socket with a hole through its bottom, a hinge member having a portion adapted to seat in said socket and having ears extending through said hole, and a hinge pin extending through said ears and seating upon the inner side of said case-section, whereby said hinge member is secured in said socket.

4. In a match box or the like, a case-section having a socket with a hole through its bottom, a hinge member having a portion adapted to seat in said socket and in peripheral engagement with the side-wall of said socket and having ears extending through said hole, and a hinge pin extending through said ears and seating upon the inner side of said case-section, whereby said hinge member is secured in said socket.

5. In a match box or the like, a case section having an aperture therein, a hinge member extending through said aperture and engaging around the same at the outer side of the case section, and a carrier secured to said hinge member at the inner side of the case section.

6. In a match box or the like, a case section having an aperture therein, a member overlapping the outer side of the case section, said member having at its inner side looped strips forming ears extending through the aperture, and a carrier secured to said ears.

7. In a match box or the like, a case section having an aperture therein, a member having a portion overlapping the outer side of said case section and another portion inside said first-mentioned portion with ears extending through the aperture, and a carrier secured to said ears.

WILLIAM E. EDWARDS.
